UNITED STATES PATENT OFFICE.

PATRICK A. TOOKEY, OF CHICAGO, ILLINOIS, ASSIGNOR TO STEREO TYPE MANUFACTURING CORPORATION, OF CHICAGO, ILLINOIS, A CORPORATION OF ILLINOIS.

MACHINE FOR CASTING STEREO TYPE PRINTING PLATES.

Application filed December 8, 1924. Serial No. 754,524.

This invention relates to machines for casting stereotype printing plates from a matrix or mat.

The principal object of the invention is to improve the construction of such machines in the particulars hereinafter more specifically referred to, and to provide, among other things, a more convenient and fully operative machine of increased efficiency and durability.

Another object is to provide means whereby interchangeable parts will give a wider range of utility to the machine.

Another object is to provide more positive means for automatically locking the movable member of the casting box or mold to the stationary member during the casting operation.

A still further object is to provide means for adjusting the said locking means, but also mounting the movable members of the mold box upon a slidable frame and providing means for shifting the same bodily toward the fixed mold member after the movable member is swung into the casting position.

Another object of the invention is to provide means for raising the clamping and adjusting means after the casting operation, so that the mold box members may be separated, and for holding the same in the raised position until said members are again brought into position for the casting of another plate.

Again, I desire to materially reduce the heating of the machine, incident to the casting operation, whereby more work may be accomplished in a given period of time and the life of the machine prolonged, by the use of a water jacket, heat absorbing fins or other suitable means applied to the stationary member of the casting box.

These and other features of the invention will be more fully comprehended as I proceed with my specification in describing the machine illustrated in the accompanying drawings.

The invention consists in the various devices, and the arrangement and combination of devices herein illustrated, described and more particularly set forth in the appended claims.

In the drawings:

Fig. 1 is a side elevation of a machine embodying my invention with the mold box

closed and ready for the metal to be poured therein.

Fig. 2 is a top plan view of the machine with the movable table member of the mold box laid down ready to receive a mat or matrix.

Fig. 3 is a longitudinal, sectional view taken in the vertical plane indicated by the dotted line 3-3 on Fig. 2.

Fig. 4 is a transverse, sectional view through the closed mold box, the section being on the horizontal plane indicated by the dotted line 4-4 on Fig. 1.

Figs. 5 and 6 are side elevations of one end of the frame, detached, to more clearly disclose certain details hereinafter described.

Fig. 7 is a sectional view of the frame, to illustrate another detail, the section being taken in the vertical plane indicated by the dotted line 7-7 on Fig. 6.

Fig. 8 is a side view of a locking lug on the movable member of the mold box.

Fig. 9 is a perspective view of the hinged, removable end bar of the mold box.

Fig. 10 is a sectional view, enlarged, showing the means for attaching the end bar to the movable member of the mold box, the section being taken in the vertical plane indicated by the dotted line 10-10 of Fig. 3.

Fig. 11 is a vertical, sectional view of a portion of the movable member of the mold box with a matrix or mat thereon and a cast stereotype plate on the mat.

Fig. 12 is a sectional detail of a portion of the stationary member of the mold box, showing a modification.

Fig. 13 is a vertical sectional view of the stationary member of the mold box showing a water-jacketed construction, as a modification.

General description.

It will be noticed by reference to said drawings, that the machine comprises a frame A, having an upright member 1, and two horizontal members 2. To the upright member is secured a vertical plate B, which forms the stationary part of the casting box. The horizontal members support a movable frame carrying a tiltable table C, adapted to hold the mat or matrix X and to be swung into juxtaposition against the aforementioned stationary part to form a mold box, the latter designated as a whole by the letter D.

The upright frame member 1 also carries the automatically acting wedges E, E, and adjustable devices F, F, for clamping the two part mold box together in the casting position; also means (levers G, G) for releasing and means (arms H, H,) for raising these clamping devices E and F, and for holding the same in the raised position ready for the next cycle of operations.

10 The horizontal frame members carry means for slidably moving the supporting part and the movable mold box member towards and away from the stationary mold box part, said means including longitudinally slidable racks I, I, actuating lever K, rack engaging segments L on the table C, and operative connections between the table C and the slidable racks I, I.

The operation is as follows: The parts 20 being positioned as shown in Fig. 3, the matrix or mat is first laid and adjusted upon the top of the table C, and the handle 3 raised, upwardly and towards the frame member 1 of the frame, the segments L rocking over the racks I until the table C and plate B come together to form the vertically positioned mold box D. The racks I, I, and table C are then bodily slid and moved toward the plate B as far as possible by actuating the lever K. Then the locking lever M will be released, whereupon the movable wedge members E and the movable clamps F will engage complementary parts to draw the table C to the plate B and tightly lock 30 these two parts together, whereupon the mold box D will be ready for the hot metal to be poured into it from a conveniently located melting pot N to make a casting Y.

When the latter has set and cooled off sufficiently to be removed, the levers G are first 40 actuated to raise the wedges and clamps, E, E, and F, F, the handle 3 grasped and drawn downwardly and away from the plate B, the table C swinging into the horizontal position and the rack moved back to first position. The locking lever M holds the wedge members and clamps in the raised position. The cast plate is removed and the operation repeated.

50

The frame.

The main frame is composed of two side, L-shaped members A, each provided with leg supports 4, a vertical standard member 1 and a horizontal member 2. The upright members 1 are provided with lugs 5, 5, by which they are attached to transverse uniting members by means of bolts 6. In the present instance, this transverse member is the plate 60 B and a table 7, the latter to support any suitable medium for heating the metal in the melting pot N, and the rock shaft 8.

The two horizontal members 2, 2, are united by the transversely positioned shaft 65 or rod 9. Between these frame members 2,

2, are the two racks L, L, the downwardly projecting, longitudinal flanges 10, 10, of which, are secured to upwardly extending flanges 11, 11, of an apertured spreader frame 12 by bolts 13, 13, or other suitable means. The levers G, G, are mounted upon the projecting end of the rock shaft 8.

The tilting table.

The table C is provided with a smooth, flat top surface 14, and downwardly projecting side flanges 15. To the latter are secured by bolts 16 the segments L, L, one on each side, the arcuate face of the segments being provided with gear teeth 17 adapted to mesh with the gear teeth 18 of the racks I, I. Pivotally secured at 19 to a flange 20, intermediate the flanges 15, is one toggle link 21, the other toggle link 22 being pivotally connected at 23 to the frame member 12, the toggles 21 and 22 being pivoted together at 24. The lever K passes through the apertured frame member 12 and its forked end 25 rests upon the rod 9. The lever K is pivoted at 26 to flanges 27 on the frame member 12. By swinging the lever K, the toggles 21 and 22 raise one end of the table C and cause the segment L to rock over the rack I. The flanges 10 of the racks I are provided with elongated, aligned slots 28 through which project pins 29 carried by the frame member 2. One end of each rack rests upon the frame member 12; thus the member 12 and the slot and pin connections just mentioned form guideways for the slideable racks I, I.

It will be noticed that the toggle 21 reaches to the floor, thus affording a support for the table C when the latter is swung into the position shown in Figs. 2 and 3.

Upon the table C at each side margin are two locking lugs 29 having a shouldered face 30 adapted for engagement by the adjustable clamping devices F, F, as herein-after more fully explained.

The table C is provided with movable bars for defining the bottom 31 and two side walls 32 of the mold box. The bar 31 is provided with rearwardly extending blocks 33, each having on its outer end a bearing recess 34 adapted to receive a hinge pin 35. A block 36 carries this hinge pin 35 and also a dowel pin 37, the latter entering a bearing recess 38 in a rearwardly extending lug 39 on the table C. Thus, when the table is in the horizontal position shown in Fig. 2, the bottom wall bar 31 may be moved away from the face of the table C, to uncover the edge of the matrix or for any other reason, by merely swinging on its hinge pin 35. If it be desired to remove the bar 31 entirely away from the table C, this may be done by simply raising it upwardly until the dowel pins 37 are free from the apertured lugs 39.

The side wall bars 32 may be adjustably or movably secured to the table C in any convenient manner. In this instance, the bars are each provided with a squared end 5 to about the front surface of the bottom wall bar 31. Said side wall bars 32 are each provided at their outer ends with a hook lever member 40 pivotally secured to a depending lug 41 and held in the normally locking position by a spring 42, which presses the hooked end of lever 40 against the under part of the table C as shown in Figs. 1 and 3. By grasping and pressing together the handle 43 on the bar and the free end of the lever 40, the bar may be shifted in its position on the table C, or removed therefrom as occasion may require. The wall bars 31 and 32 are shown of conventional size, i. e., type high, but when it is necessary to make a thin casting, these are removed and thinner metal used. To accommodate, therefore, a mold box having a cavity for a plate other than of conventional or standard thickness, it is necessary to provide the machine with adjustable means for clamping the mold box members together. This I accomplish by the lugs 29, 29, and the clamping devices F, F.

The devices F, F, are pivotally mounted at 43 to the movable wedge members E, E, and are provided on their hooked or outer ends with an adjustable bolt 44, the head of which is adapted for contact with the inclined or wedge surface 30 of the lugs 29 when the table C is in the position shown in Figs. 1 and 4. By adjusting the bolt 45 in or out, the clamp F will accommodate itself to walls 31, 32, of any required thickness. And, for the convenience of the user, I prefer to provide a handle 46 for the table C.

The wedge adjustment.

On each side margin of the stationary, vertical plate member B is a flange 47 provided at its rear margin with an upper and a lower inclined surface 48. Immediately in rear of each flange 47 is a vertically movable wedge member E having at its forward margin or edge two inclined surfaces 49, complementary to and adapted to bear against the inclined surface 48 on the flange 47. The members E, E, are supported upon the lifting levers G, by means of pins 50 which pass through elongated slots 51 in the levers G.

The raising arms H, H, are secured to the wedge members E and project forwardly under the clamp members F, to hold the latter in position to ride over the lugs 29 when the table C is brought up to the plate B and also to raise the members F upwardly, out of engagement with said lugs, when the wedge members E are raised by the levers G.

The locking levers M are pivotally mounted on the frame members 2 in such position as to support upon their upper end 52, the lower end 53 of the wedge members E, when the levers M are in their normal or locking position as shown in Figs. 5 and 6. A spring 54 secured at one end to the frame and at its other end to an arm 55 on the lever M, immediately returns the lever M to its vertical and locking position, as soon as the wedges E are raised. A handle or lug 56 on the lever M enables the operator to move the lever out from under the wedge E (unlocking the wedge), into the position shown in Fig. 1 where the wedge is shown lowered.

From this description, it will be understood that when the table C, with its mat or matrix positioned thereon between the walls 31, 32, 32, is brought up towards the plate B, it is first of all moved as closely to said plate as possible, by actuating the lever K and its operative connections. Then the operator actuates the lever M and immediately the weight of the two wedges E, E, causes them to drop from the positions indicated in Figs. 5 and 6, to that indicated in Fig. 1, whereupon by reason of the complementary wedge surfaces 48 and 49, the table C will be clamped to the plate B. At the same time, the clamps F engage the four lugs 29. The operator will usually "tighten" the wedges by downward pressure on the handles G. The mold box is now tightly formed and the operator may pour molten metal from the receptacle N into the mold cavity, for the casting of the stereotype plate Y desired.

When it is desired to open the mold box, the operator raises the levers G until the end of wedge E is above the end of the locking lever M, which latter will promptly engage the wedge and lock it in the raised position. The clamps F, F, are raised simultaneously with the wedges E, E, and then the operator may grasp the handle 46 and lower the table C to the open position shown in Fig. 2, and remove the casting Y. He may replace the matrix X with another and repeat the operation, or may lock up the mold box with the first matrix in position and make a second casting.

In Fig. 12, I show a slightly modified form of the plate member B in this, that on the back, at convenient intervals, I may cast a plurality of heat absorbing fins 57. When these are used, it will be found that hot metal used in casting will not heat up the plate B so quickly as it would without them, and the life of the plate B is not only lengthened, but the intervals between cycles of casting may be materially shortened.

In Fig. 13, I show another modification for decreasing the tendency of the plate B to become unduly heated, by the employ-

ment of a water jacket. A simple form of water jacket consists of bolting or casting a back wall 58 to the back of the plate B, with the upper and lower tapped openings, 5 59, 59, for attachment therein of any conventional means (not shown) of piping to a source of cold water supply and to a drain.

It will be understood, of course, that the 10 cooling jacketed plate B may be supplied with any cooling medium, other than water, such for example as cooled air, and the term "water cooled jacket" used herein will be understood to mean any jacketed space on the plate B adapted to receive such cooling medium.

It will also be understood that when the mold box is provided with bottom and end walls other than the type high walls 31 and 20 32 shown, the bodily shifting of the table C, by the actuation of the lever K together with the adjustability of the bolts 44 in the clamps E, will compensate for the difference 25 in thickness and permit plates of different thickness to be cast.

I claim—

1. A machine for casting stereotype printing plates, comprising a frame member having a vertically disposed plate, a movable table provided with side and end wall members, means for moving said table and wall members into position against said plate to form a mold box, and means on the frame for automatically engaging the table and locking the mold box members together, said means including a wedge member, a clamp

30 pivotally mounted on the wedge member, the wedge cooperating with the plate and the clamp with the table.

40 2. A machine for casting stereotype printing plates, comprising a frame member, a vertically disposed fixed plate secured thereto, a movable table, end and side walls on the table, means for moving said table and walls in position against said plate to form a mold box, vertically movable wedges operatively connected with the frame, one on each side, and with inclined surfaces on the plate, lugs on the table and clamping bars pivotally connected to said wedges and adapted to engage said lugs.

45 3. A machine for casting stereotype printing plates, comprising a frame member having a vertically disposed plate, a movable table provided with side and end wall members, means for moving said table and wall members into position against said plate to form a mold box, and means on the frame for automatically engaging the table and locking the mold box members together, said means including a wedge member, a clamp

50 pivotally mounted on the wedge member, the wedge cooperating with the plate and the clamp with the table, and means on the frame for actuating the wedge member into the unlocking position.

4. A machine for casting stereotype printing plates, comprising a frame member having a vertically disposed plate, a movable table provided with side and end wall members, means for moving said table and wall members into position against said plate to form a mold box, and means on the frame for automatically engaging the table and locking the mold box members together, said means including a wedge member, a clamp 70 pivotally mounted on the wedge member, the wedge cooperating with the plate and the clamp with the table, and means on the frame for actuating the wedge member into the unlocking position, said means including a rock shaft on the frame, a slotted lever on the shaft and a pin or stud on the wedge member engaging said slotted lever.

5. A machine for casting stereotype printing plates, comprising a frame member having a vertically disposed plate, a movable table provided with side and end wall members, means for moving said table and wall members into position against said plate to 80 form a mold box, and means on the frame for automatically engaging the table and locking the mold box members together, said means including a wedge member, a clamp pivotally mounted on the wedge member, the wedge cooperating with the plate and the clamp with the table, and means on the frame for actuating the wedge member into the unlocking position.

6. A machine for casting stereotype printing plates, comprising a frame member having a vertically disposed plate, a movable table provided with side and end wall members, means for moving said table and wall members into position against said plate to 90 form a mold box, and means on the frame for automatically engaging the table and locking the mold box members together, said means including a wedge member, a clamp pivotally mounted on the wedge member, the wedge cooperating with the plate and the clamp with the table, and means on the frame for actuating the wedge member into the unlocking position.

7. A machine for casting stereotype printing plates, comprising a frame member having a vertically disposed plate, a movable table provided with side and end wall members, means for moving said table and wall members into position against said plate to 100 form a mold box, and means on the frame for automatically engaging the table and locking the mold box members together, said means including a wedge member, a clamp pivotally mounted on the wedge member, the wedge cooperating with the plate and the clamp with the table, and means for holding the wedge member in the unlocking position.

- position, comprising an arm pivoted on the frame adapted at one end to engage the wedge member and a spring on the frame connected to the arm.
- 5 8. A machine for casting stereotype printing plates including a fixed plate constituting one face of the mold box, a movable table constituting another face of the box, and a bottom wall for the mold box, said 10 wall comprising a single bar provided with lugs and hingedly positioned on the movable table.
9. A machine for casting stereotype printing plates including a fixed plate constituting one face of the mold box, a movable table constituting another face of the box, and a bottom wall for the mold box, consisting of a bar, rearwardly extending, 15 projections on the bar, a block removably positioned on the movable table and hingedly connected with said recessed extensions.
10. A machine for casting stereotype printing plates comprising a frame, a vertically disposed plate on the frame, spaced apart 20 racks horizontally mounted on the frame, a table movably supported on the racks and means for tilting said table from a horizontal to a vertical position, and means for giving a longitudinal bodily movement to 25 the racks and the table.
11. A machine for casting stereotype printing plates comprising a frame, a vertically disposed plate on the frame, spaced apart 30 racks horizontally mounted on the frame, a table movably supported on the racks and means for tilting said table from a horizontal to a vertical position, and means for giving a longitudinal bodily movement to 35 the racks and the table, comprising a fulcrum shaft on the frame, a slotted member to which the racks are secured, connections 40 to between the table and said member, and an actuating lever pivoted to the slotted member and fulcrumed on said shaft.
12. A machine for casting stereotype printing plates comprising a frame, a vertically disposed plate on the frame, spaced apart 45 racks horizontally mounted on the frame, a table movably supported on the racks and means for tilting said table from a horizontal to a vertical position, and means for giving a longitudinal bodily movement to 50 the racks and the table, comprising a fulcrum shaft on the frame, a slotted member to which the racks are secured, connections 55 to between the table and said member, and an actuating lever pivoted to the slotted member and fulcrumed on said shaft, said connections comprising a pair of toggle links, the one connected to the table being 60 sufficiently long to reach the ground to act as a standard or support for the table.
13. A machine for casting stereotype printing plates, comprising a frame member having a vertically disposed plate, a movable 65 table provided with side and end wall members, means for moving said table and wall members into position against said plate to form a mold box, and means on the frame 70 for automatically engaging the table and locking the mold box members together, said means including a wedge member and a clamp pivotally mounted thereon, a clamp 75 surface on the table and means on the clamp for adjusting its contacting surface to co-operate with the contacting surface of the table.

In testimony that I claim the foregoing as my invention I affix my signature this 3rd day of December, 1924.

PATRICK A. TOOMEY.
